UNITED STATES PATENT OFFICE.

ANTHONY DIXON BROGAN AND ANDREW MURRAY MALLOCH, OF GLASGOW, SCOTLAND.

DESIGN FOR THE SURFACE ORNAMENTATION OF SHEET-GLASS.

SPECIFICATION forming part of Design No. 22,356, dated April 18, 1893.

Application filed January 18, 1893. Serial No. 458,841. Term of patent 14 years.

To all whom it may concern:

Be it known that we, ANTHONY DIXON BROGAN and ANDREW MURRAY MALLOCH, citizens of the United Kingdom of Great Britain and Ireland, residing at Firhill, Glasgow, in the county of Lanark, Scotland, have invented and produced a new and original Design for the Surface Ornamentation of Glass, of which the following is a specification, reference being had to the accompanying drawings, forming part thereof.

Figure 1 is a plan or face view of our design and Fig. 2 is a section on the line $x-x$ Fig. 1.

15 The design is for the surface ornamentation of glass and as represented in the annexed drawings it consists of a series of panels, the spaces between the panels being occupied by figures of a different design to the first named series, the first named series of panels each containing a rayonnant figure bounded by octagonal lines 1 the lines 2 forming the rayonnant figure being alternately in intaglio and in relief so as to produce triangular facets in the application of the design on the 25 surface of the glass. The spaces between the octagonal boundary lines of the rayonnant

figures which are arranged symmetrically in rows are occupied by cross lines 3 in the plane of said boundary lines 1 and other lines 4 in inclined planes such as to produce a symmetrical group of approximately pyramidal figures in intaglio the outline of the group being co-terminous with the boundary lines of the rayonnant figures and resembling a four 35 pointed star.

The white portions of the design represent the facets struck by the light and the darkened portions the facets in shade.

We claim—

40 The design for the surface ornamentation of glass substantially as herein shown and described.

In witness whereof we have hereunto set our hands and seals the twelfth day of December, 45 1892.

ANTHONY DIXON BROGAN. [L. S.]
ANDREW MURRAY MALLOCH. [L. S.]
